FIG. 1

FIG. 1 is a perspective view of a pool with an integral slide and ladder showing our design;

FIG. 2 is a plan view thereof to a reduced scale;

FIG. 3 is a side elevational view thereof on the same scale as FIG. 2;

FIG. 4 is a fragmentary sectional view thereof along the line 4-4 of FIG. 2 and to an enlarged scale;

FIG. 5 is an end elevational view thereof on the same scale as FIG. 2;

FIG. 6 is an elevational view of the end opposite that illustrated in FIG. 5; and

FIG. 7 is a fragmentary sectional view thereof along the line 7-7 of FIG. 5 and to an enlarged scale.

The characteristic feature of our design resides in the ogee curve configuration of the slide which cooperates with the similar ogee curve configuration along the one side of our pool.

We claim:

The original design for a pool with integral slide, as shown and described.
